Attorney

UNITED STATES PATENT OFFICE

2,504,761

COMBINATION SLEEPING BAG
AND BLANKET

Joseph J. Turco, Franklin, Mass.

Application January 28, 1948, Serial No. 4,845

2 Claims. (Cl. 2-69.5)

1

My invention relates to a combination blanket and sleeping bag for use by infants and young people and it has for its object to provide an article of the character described which can be utilized either as a blanket covering or as a sleeping bag and in both instances provide an end flap extension to occupy a position behind or beneath the head of the user of the device to serve either as a head rest, or as a windbreak for shielding the head of the user.

To these ends I have provided an article of the class described comprising a bag-shaped body consisting of a bottom ply of flexible sheet material and a top ply also of flexible sheet material, joined together along their opposite sides and bottom, said bag-shaped body portion being provided at its head end with a two-ply flap extension whose transverse intermediate portion is separated from said head end by a slit whose opposite sides are provided with slide-operated means for separably connecting the said transverse intermediate portion to the bottom ply of said bag-shaped body portion thereby to provide for use of the structure in different ways.

Other features of the invention are hereinafter pointed out.

In the accompanying drawings:

Figure 1 is a perspective view of my improved combination blanket and sleeping bag as viewed from the top thereof and with the transverse slit, hereinafter described, secured in its closed condition.

Figure 2 is a similar view showing the opposite sides of the slit disconnected.

Figure 3 is a longitudinal section on line 3—3 of Fig. 1.

Figure 4 is a transverse section on line 4—4 of Fig. 2.

The illustrated embodiment of the invention is an approximately oblong structure made in most part from two superposed pieces of pliable sheet material of the same size and shape having their outer marginal portions stitched or otherwise fastened together as shown in Figs. 3 and 4 and comprises a bag-like body portion 10 including a bottom ply 11 and a top ply 12.

The head end of this bag structure comprises a two-ply flap extension 13 including a bottom ply 14 (Fig. 3) that is integrally connected adjacent to the opposite sides of the device with the bottom ply 11 of the bag-like body portion 10, while the top ply 15 of this extension is likewise integrally connected, adjacent to the opposite sides of the device, with top ply 12 of said bag-like body portion.

2

At the mouth of the bag-like body portion 10 the bottom ply 11 thereof has secured to it a zipper fastener element including a row of lugs 16 while a complementary zipper element including a row of zipper lugs 17 is secured to the inner marginal portion of the two-ply flap extension 13. These two rows of zipper lugs are interlocked and disconnected by means of the usual slide 19 co-operatively associated therewith in the well known manner. Thus the flap extension 13 can be securely connected with, and can be readily disconnected from, the end of the bottom ply 11 of body portion 10 at will.

When the inner marginal portion of the two-ply flap extension 13 is connected, through adjustment of slide 19, with the bottom ply 11 of body portion 10 and an infant is inserted within the bag, feet first, the flap extension 13 can be utilized either as a head rest, as a wind-break, or both.

On the other hand when the inner marginal portion of two-ply flap extension 13 is disconnected from the bottom ply 11 of body portion 10 as shown in Fig. 2, said body portion 10 may be utilized as a two-ply blanket over the infant whose head may extend through the slit 20 then existing between flap extension 13 and bottom ply 11 so that said flap extension may continue to be utilized as a head rest and wind-break.

Fastened at 21, 21, to each side of the flap extension 13 is a strand or ribbon 22 and when the child is within body 10 with its head resting upon the flap extension, or while utilizing the body 10 as a blanket with the child's head extending through slit 20 and resting upon said flap extension, the sides of the latter can be drawn inwardly by means of the strands or ribbons into positions against the opposite sides of the head of the child and secured in those positions by tying the two strands together.

In practice I may, as shown, make the top plies of the bag and flap extension from the pelt of a mammal such as sheepskin, the fur side thereof being disposed outermost. Such material not only enhances the appearance of the device but also adds to the comfort of the child, especially in cold weather. The bottom plies 11 and 14 of the bag and flap extension, respectively, may be made from quilted textile fabric as indicated in Figs. 2, 3 and 4.

From the above description it will be seen that the preferred embodiment of the invention illustrated in the drawings is produced, in most part, from two oblong pieces of flexible sheet material of the same size and shape disposed one upon the other and having their marginal portions sewed

together throughout the circuit of the device, said two pieces being formed with registering transverse slits disposed in closer proximity to one end of the composite structure than they are to the opposite end thereof so as to provide a two-ply extension flap 13 for use as a head rest and/or wind-break while the device is being employed either as a sleeping bag or as a blanket, it being also noted that these slits end at points spaced away from the opposite sides of the structure.

It will also be clear from the above description that the well known fastener element including the studs 17 is fastened in any suitable manner, as by stitches or cement, to both plies of the extension flap 13, while the usual complementary fastener element including the studs 16 is fastened in any suitable manner, as by stitches or cement, only to the bottom ply 11 of the body 10. The fastener elements 16, 17 and 19 are quite desirable but they are not essential to this invention in its broader aspects.

What I claim is:

1. A combination sleeping bag and blanket comprising two approximately oblong pieces of flexible sheet material of the same size and shape disposed one upon the other and having their marginal portions joined throughout their extent; registering transverse slits formed in said two plies in closer proximity to one end of the structure than they are to the opposite end thereof so as to provide a bag-like body and a two-ply flap extension at the open end thereof for use as a head rest or as a wind-break; a row of fastener lugs secured to the marginal portions of the two plies of said extension which border said slits; a row of fastener lugs secured to the marginal portion of

said bottom ply of said body which borders the slit formed therein, and a slide member co-operatively associated with said two rows of lugs and by which the latter are interlocked and also disengaged.

2. A combination sleeping bag and blanket structure comprising two oblong plies of flexible sheet material of the same size and shape including a top ply superimposed upon a bottom ply, and means fastening together the outer marginal portions of said two plies throughout their extent, said two plies being formed with registering transverse slits between their oppositely disposed longitudinal sides and in proximity to one end of the structure to provide the latter with a bag-like body portion having a two-ply flap extension at the head end thereof; means permanently connecting the transverse marginal portions of the two plies of said flap extension which border said slits, and means for separably fastening said connected marginal portions of the two plies of said flap extension which border said slits to the proximate end of the bottom ply of said bag-like body portion.
